PERINEAL BATH

E. Peter Robare, Louisville, Ky., assignor to American Standard Inc., New York, N.Y., a corporation of Delaware

Continuation-in-part of design application Ser. No. 4,000, Sept. 23, 1966. This application Mar. 26, 1968, Ser. No. 11,147

Term of patent 14 years

U.S. Cl. D23—51

Int. Cl. D23—02

Fig. 1.

Fig. 2.

Fig. 3

Fig. 4

FIGURE 1 is a front perspective view of a perineal bath embodying my new design;

FIGURE 2 is a side perspective view of the perineal bath showing the new design;

FIGURE 3 is a top view of the perineal bath showing the new design; and

FIGURE 4 is a rear view of the perineal bath.

This application is a continuation-in-part of application D.4,000, filed Sept. 23, 1966, and now abandoned.

What is claimed is:

The ornamental design for a perineal bath, substantially as shown.
